UNITED STATES PATENT OFFICE.

WILLIAM D. RUNDLETT, OF NORTH ANDOVER, MASSACHUSETTS, ASSIGNOR TO DAVIS AND FURBER MACHINE CO., OF NORTH ANDOVER, MASSACHUSETTS, A CORPORATION OF MASSACHUSETTS.

MULE.

1,255,934.

Specification of Letters Patent. Patented Feb. 12, 1918.

Application filed July 18, 1917. Serial No. 181,206.

To all whom it may concern:

Be it known that I, WILLIAM D. RUNDLETT, a citizen of the United States, residing at North Andover, county of Essex, State of Massachusetts, have invented an Improvement in Mules, of which the following description, in connection with the accompanying drawing, is a specification, like characters on the drawing representing like parts.

This invention relates to mules such as are used for spinning yarn and particularly to the driving connection between the driving mechanism and the drums or cylinders from which the spindles are rotated.

The invention has for its object to provide a driving connection of this character which will enable the drum or drums to be readily disconnected from the driving mechanism. The main shaft of the driving mechanism is removable first, to enable repairs to be made such as are not infrequently required in connection with the usual backing off ratchet gear and the usual winding clutch gear; second, to enable required changes to be made in the speed ratios between the spindles and the drum or cylinder as when the size of the bobbins are changed or as when a change is made from winding bobbins to winding cops and vice versa. The driving mechanism with its shaft usually intervenes between two drums and the disconnection has to be made at one end for some purposes and at the other end for other purposes. This invention enables the desired disconnection and connection readily to be made between the driving mechanism and the drums or cylinders.

The invention also has for its object to provide a driving connection of this character which will secure a certain amount of flexibility. In an ordinary type of mule, the shaft of the driving mechanism is approximately two feet in length while the drums to which it is connected are between thirty-five to forty-five feet in length, and the transverse width of the carriage is relatively small. The entire carriage is operated backward and forward from its center portion. Owing to these facts, there is necessarily more or less of a flexion. Furthermore, misalignment is liable to occur between the drums and driving mechanism because the drums are adjustable toward and from the spindles which may cause a misalign-

ment horizontally and the floors or track may be or may settle unevenly causing misalignment vertically. Such misalignments when they occur and such flexion of the carriage places a great strain upon the driving mechanism and its shaft because the cylinders, owing to the fact that they are cylindrical and of considerable diameter, are substantially rigid. This invention provides in the driving connection a sufficient amount of flexibility to remove these strains from the driving mechanism and its shaft.

In order to give an understanding of my invention, I have illustrated in the drawings a selected embodiment thereof which will now be described, after which the novel features will be pointed out in the appended claims.

Figure 1 of the drawings is a sectional view through the carriage of a mule showing one of the spindles and the driving drum;

Fig. 2 is a fragmentary view showing in plan view the driving mechanism for the drums, said view being partially in section to show better the driving connection between the driving mechanism and one of the drums;

Fig. 3 is an enlarged sectional view through one end of the drum showing the driving connection between it and the driving shaft;

Fig. 4 is an enlarged view of the driving connection disconnected from the drum;

Fig. 5 is a view of the head on the driving shaft;

Fig. 6 is a side view of the coupling member;

Fig. 7 is an enlarged sectional view on the line 7—7, Fig. 3;

Fig. 8 is a view of the nut-lock;

Fig. 9 is an enlarged view of a portion of the head showing the rounded rim.

Inasmuch as my invention relates simply to the drums from which the spindles of a mule are operated and the driving connections therefor, I have not thought it necessary to illustrate herein the complete mule structure, but have contented myself with illustrating in the drawings a sufficient portion of a mule merely to enable the invention to be understood.

I have shown at 1 the carriage of a mule (said carriage being shown in section) in which the spindles 2 are journaled in usual manner and which is provided with the

drum or cylinder 3 from which the spindles are rotated in usual manner by means of the belts or bands 4 which pass around the drum and around the whirls 5 of the spindles. 5 The carriage is illustrated as moving back and forth on the track 6. 7 indicate the usual drawing rolls and 8 and 9 are the winding and counter-fallers, respectively, which are brought into action at the proper 10 time to assist in winding the spun yarn on the spindles and maintain it at the proper tension. The drum or cylinder 3 of a mule is usually made in sections situated in alignment, and a suitable driving connection is 15 mounted on the carriage between the adjacent ends of the drum sections and is coupled to said sections for driving the same. Such a driving connection is shown in Fig. 2 sufficiently for the purposes of this application, and it comprises a driving shaft 10 sustained in suitable bearings 11 on the carriage 1 and provided with one means for rotating it when the carriage is moving outwardly during the drawing and twisting operation, and with another mechanism for 25 rotating it when the carriage is moving inwardly during the winding operation.

The driving shaft is driven during the spinning or drawing and twisting operation 30 by means of a pulley 12 fast thereon and which is actuated by the usual rope drive. The shaft 10 is driven during the winding operation from the usual winding chain drum 13 which has a gear 14 rigid therewith which meshes with a wide-faced gear 15 which is slidably mounted on the shaft 10. This gear has a clutch member 16 rigid therewith which is adapted to be moved into engagement with a clutch member 17 fast 35 on the shaft 10, thus clutching the gear 15 to the shaft. The gear 15 is moved longitudinally of the shaft to clutch it to or unclutch it from the clutch member 17 by means of an actuating lever 180 which is operated 40 in usual manner.

The above-described form of driving mechanism is such as is commonly used in spinning mules and will, therefore, be understood by those skilled in the art without 45 any further explanation.

The shaft 10 is coupled to the drum sections 3 by a novel coupling which is constructed to permit the shaft to be readily disconnected from the drum in case it is 50 desired to change one driving mechanism for another and which also has a certain amount of flexibility so that there will be no binding action even though the drums and shaft are not in absolute alignment.

60 The driving drums 3 are usually in the form of a sheet metal cylinder which is supported at its ends on heads 18. 19 designates a head which is secured to the end of the shaft 10, said head being herein shown as 65 keyed to the shaft, as shown at 20. This

head 19 is in the form of a disk and is provided with two openings 21 that are adapted to receive driving projections 22 that extend from a coupling member 23 which in turn is secured to the head 18. The coupling 70 member 23 is shown in side view in Fig. 6 and it presents a rim portion 24 having a flange 25 extending inwardly therefrom, said flange having the projections 22 formed thereon. The coupling member 23 may be 75 detachably secured to the head 18 in various ways. I have herein shown for this purpose two screws or bolts 26 which extend through apertures 27 formed in the projections 22 and which are screw-threaded into the head 80 18, as shown at 28. The heads 29 of these bolts or screws bear against the outer face of the projections 22 and thus clamp the coupling member to the head. The head 18 is rabbeted at its edge, as shown at 30, 85 thereby to form an annular shoulder, and the coupling member is made with the lip 31 which fits over the shoulder. By this means the coupling member 23 is rigidly but detachably secured to the head of the drum. 90 The rim 24 of the coupling member is provided with the inner annular surface 32 having the same diameter as the exterior diameter of the head 19, and when the parts are 95 in operative driving position, the head 19 sits within the surface 32 as indicated in Fig. 3. The rim of the head 19 is rounded or curved transversely, as shown in Fig. 9, the curvature being on the arc of a circle struck from the point 33 as a center. The 100 object of this construction is to permit a slight rocking movement of the shaft 10 relative to the drum without causing any binding of the parts.

The apertures 21 are slightly larger than 105 the driving projections 22 and there is thus provision for a certain amount of rocking motion between the driving head 19 and the coupling member 23 which prevents any binding even though the drum and the 110 shaft are not in absolute axial alignment. The engagement of the periphery of the head 19 with the annular surface 32 of the coupling member holds the coupling member and head 19 in proper relative position 115 axially and prevents any lateral movement of one relative to the other.

If it is desired to disconnect the shaft 10 from the drum and then to remove either the shaft or the drum, the clamping screws 120 26 are first removed and then the coupling member 23 is shifted to the right, Fig. 3, sufficiently to withdraw the lip 31 thereof from the shoulder 30, the relative shape 125 of the parts 19 and 23 being such as to permit of such movement. When the coupling member 23 is thus separated from the shoulder 30, the shaft 10 with the head 19 and coupling member thereon can be removed 130 without shifting the position of the drum.

The head 19 is shown as being held on the shaft 10 by means of a nut 34 which is screw-threaded to the reduced end 35 of the shaft. This nut is locked on the shaft by means of a nut-lock 36, best seen in Fig. 8. This nut-lock is provided with a central opening 37 of a size to sit over the nut, the edge of the opening being formed on opposite sides with notches 38, 39 which are shaped to receive the corner of the nut 35. The nut-lock is provided with ears 40 having slots 41 therein to receive clamping screws 42 which are screwed into the head 19. In using the nut-lock the nut is first screwed up tight and then the nut-lock is placed over the nut so that two of the opposite corners of the nut will be engaged in either the notches 38 or 39 when the slots 41 are positioned over the screw-threaded apertures for the bolts 42. The bolts 42 are then inserted through the slots and screwed into the head 19, thus preventing the nut-lock from turning. By this means the nut 35 is securely locked in position.

25 The device herein illustrated is such that the shaft can be disconnected from the drum with great facility, as this operation involves simply removing the screws 26 and sliding the coupling member 23 axially. The 30 device also has the advantage that it provides a flexible coupling which will transmit the rotation of the shaft 10 to the drum without putting the latter under any strain such as might be caused if the shaft and 35 drum were rigid with each other.

I claim:

1. In a mule, the combination with a carriage, of a plurality of spindles journaled therein, a drum rotatably mounted on the carriage and from which the spindles are driven, a drum-driving mechanism on the carriage including a driving shaft, and a flexible coupling between said shaft and drum.
- 45 2. In a mule, the combination with a carriage, of a plurality of spindles journaled therein, a drum rotatably mounted on the carriage and from which the spindles are driven, a drum-driving mechanism on the carriage including a driving shaft, and means for detachably but flexibly coupling said shaft and drum.
- 50 3. In a mule, the combination with a carriage having spindles journaled thereon, of a spindle-driving drum on the carriage, said drum having a head, a drum-driving

mechanism on the carriage including a driving shaft, a head on said shaft, and a coupling member secured to the head of the drum and flexibly connected to the head on 60 the shaft.

4. In a mule, the combination with a carriage having spindles journaled thereon, of a spindle-driving drum on the carriage, said drum having a head, a drum-driving mechanism on the carriage including a driving shaft, and a coupling member detachably secured to the drum and flexibly connected to the driving shaft.

5. In a mule, the combination with a carriage having spindles journaled therein, of a spindle-driving drum on the carriage, said drum having a head, drum-driving mechanism on the carriage including a driving shaft, a circular head on said shaft provided with apertures, a coupling member rigid with the head of the drum and having driving projections which occupy said apertures and also provided with a positioning rim which encircles the head on the shaft.

6. In a mule, the combination with a carriage having spindles journaled thereon, of a spindle-driving drum rotatably mounted on the carriage, drum-driving mechanism including a driving shaft, a disk-like head 85 on said driving shaft having its peripheral edge convexly curved in an axial direction and provided with openings, a coupling member rigidly secured to the drum and provided with driving projections occupying the openings of the head and also provided with a positioning rim portion which encircles and contacts with the peripheral edge of said head.

7. In a mule, the combination with a carriage having spindles journaled thereon, of a spindle-driving drum rotatably mounted on the carriage, drum-driving mechanism including a driving shaft, a disk-like head on said driving shaft having its peripheral edge convexly curved in an axial direction and provided with openings, a coupling member detachably but rigidly secured to said drum and provided with driving projections occupying the openings of the head 100 and also provided with a positioning rim portion which encircles and contacts with the peripheral edge of said head.

In testimony whereof I have signed my name to this specification.

WILLIAM D. RUNDLETT.
